PERSONNEL PLATFORM FOR FORK LIFT

Jack L. Dane, Plymouth, Mich., assignor to Ford Motor Company, Dearborn, Mich., a corporation of Delaware

Filed May 31, 1962, Ser. No. 199,194
4 Claims. (Cl. 182—222)

This invention relates to platforms for mounting on the lifting forks of a fork lift for elevating personnel to reach high, otherwise inaccessible places.

In factories, warehouses and other places, it is frequently necessary or desirable to perform work at locations elevated a number of feet above the floor. A fork lift often is available for lifting to such elevations. The present invention is directed to a personnel platform specifically constructed for locking to the lifting forks of a fork lift to provide a safe and convenient floor for personnel which can be elevated to any height within the lifting limits of the fork lift.

The platform of the present invention is provided with an interlock for engaging behind the heel of the lifting forks to retain the platform on the forks and prevent accidental disengagement. The platform is capable of use with conventional lifting forks or fork lifts without any modification of the forks, and provides a positive interlock between the platform and the forks without the necessity of drilling or otherwise weakening the forks.

Among the objects of the present invention are to provide a platform for fork lifts that will inter-fit with conventional lifting forks without modification of the forks, that will make positive locking engagement with the forks, and that is simple and dependable in operation and economic to manufacture.

Other objects, and objects relating to details and economies of construction and use, will be present from the detailed description to follow.

My invention is clearly defined in the appended claims. In the claims, as well as in the description, parts may at times be identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawings forming part of this specification, in which:

FIGURE 1 is a perspective view of a personnel platform constructed according to the present invention, the platform being shown at rest upon a floor.

FIGURE 2 is a perspective view of the platform after being elevated by lifting forks of a fork lift.

FIGURE 3 is a diagrammatic side elevation showing the manner in which the lifting forks are entered beneath the platform when it is at rest on a floor.

FIGURE 4 is a view similar to FIGURE 3, showing the platform immediately after it has been lifted from the floor.

FIGURE 5 is a view similar to FIGURE 3 of the platform ready for operation.

Referring now to the drawings, the personnel platform of the present invention has a rectangular sheet metal floor 10 which may be provided with stiffening angles 11 about its periphery. Railings 12 and 14 project upwardly from the angles 11 on two opposite sides of the platform, the railings preferably being formed of sections of pipe. A gate 5 pivotally mounted on the railing 12 extends across a third side of the platform and is provided with a latch 16 for engaging the railing 14.

The fourth side of the platform is provided with a railing formed of a frame 17 covered with wire mesh 18 and which preferably projects somewhat higher than

2

the railings 12 and 14 and is pivotally mounted at its lower edge for swinging about a horizontal axis extending generally along the adjacent edge of the platform. Preferably, the frame 17 is carried by a pair of pins 19—19, each pin extending between a pair of angles 20—20 arranged back-to-back and mounted on the adjacent stiffening angle 11.

A pair of sliding latches 21 are mounted on the frame 17, the latches being spring-pressed axially against plates 22 and 24 mounted on the railings 12 and 14, respectively. Holes 25 in the plates 22 and 24 receive the latches 21 to hold the frame 17 latched either in inwardly rotated position, as shown in FIGURES 1 and 2, or outwardly rotated position, as shown in FIGURE 5.

The underside of the sheet metal floor 10 is provided with elements which may be in the form of angles 26 mounted back-to-back in spaced relation and, with the base, defining a pair of parallel channels on the underside of the base for receiving the tines of a pair of lifting forks. The angles 26 project outwardly beyond the edge of the base below the frame 17 for a short distance as indicated in FIGURE 1. Preferably, a reinforcing plate 27 is welded to the outer edges of the angles 26.

A plate 29 is welded across the ends of each pair of angles to partially close the ends of the two channel formations formed by the angles. The plate 29 extends only a portion of the distance up towards the bases of the angles. The function of the plates 29 will be described in more detail hereinafter.

A pair of swingable supports 30 are pivotally mounted on the underside of the floor 10, the bases 33 of the supports preferably being closer to the edge of the floor beneath the gate 15 than to the opposite edge so that when the platform is resting on the floor or other supporting surface, it will rest on the supports 30 and the projecting ends of the angles 26, as indicated in FIGURES 1 and 3.

Each support 30 has an upwardly projecting arm 31 which is connected by a link 32 with the pivotally mounted frame 17. The linkage is such that when the frame 17 is folded inwardly as indicated in FIGURES 1 and 3, the supports 30 extend downwardly to support the floor 10 at an angle to the supporting surface. When the frame 17 is rotated outwardly into a plane perpendicular to the floor 10, the supports 30 are retracted as indicated in FIGURE 5.

A fork lift 34 is indicated in broken lines in FIGURES 3—5. The fork lift 34 has a mast 35 and a pair of spaced lifting forks, one fork 36 being shown. The lifting forks are conventional and have generally horizontally projecting tines, one tine 37 being shown. The height of the support 30, the projection of the angles 26 beyond the edge of the floor 10, and the height of the plates 29 connecting the projecting ends of the angles 26 are such that, with the platform resting on the floor as indicated in FIGURE 3, the tines may be entered horizontally between the edge of the floor 10 and the top of the plates 29, one of the tines of the fork lift being entered between the backs of each pair of angles 26.

Prior to engaging the fork lift with the platform, the frame 17 is rotated inwardly to permit entrance of the mast between the railings 12 and 14 as the tines 37 are inserted completely beneath the floor 10. Then, by lifting the forks, the platform will tend to rotate on the forks about the edge of the floor 10, the floor resting completely on the tines, and the tines lying between the pairs of angles 26 to prevent movement of the platform laterally of the tines. At the same time, as the floor 10 moves to level position on the tines, the plate 29 extending across the projecting ends of each pair of angles 26, rises behind the heel 40 of the lifting forks 36 as indicated in

FIGURE 4 to prevent the platform from slipping forwardly from the tines. After thus engaging the tines with the platform, the frame 17 may be moved outwardly into latched position, thereby retracting the supports 30 and clearing the floor 10 for use.

To disengage the platform from the lifting forks, the operation may be reversed. After the platform has been lowered to a position near the ground, the frame 17 is swung inwardly, extending the supports 30. Then, the lifting forks are lowered until the platform is again resting on the supports 30 and the projecting ends of the angles 26. The tines then can be withdrawn from the platform.

The above-described construction provides a personnel platform which is usable with conventional fork lifts without modifying the lifting forks, and at the same time, the platform is positively retained on the forks so that it cannot become dislodged in use.

What is claimed is:

1. A platform for mounting on the lifting forks of a fork lift, said platform having a flat base, means on the underside of the base forming a pair of parallel elements for receiving the tines of the lifting forks, said elements projecting beyond an edge of the base and each element having a portion adapted to lie behind the heel of a tine to prevent fortuitous disengagement of the platform from the tines, support means projecting downwardly from the base to support the platform with the base inclined at a substantial angle to a supporting surface, said inclination of the base being sufficient, and said portions being low enough to permit entrance and withdrawal of the tines from the elements when the portion of the base above the free ends of the tines is raised substantially above the tines to tilt the base, the platform having a railing about its periphery and a section of the railing adjacent the

35

tine-entering side of the base being swingable inwardly above the platform.

2. A platform for mounting on the lifting forks of a fork lift, said platform having a flat base, means on the underside of the base forming a pair of parallel elements for receiving the tines of the lifting forks, said elements projecting beyond an edge of the base and each element having a portion adapted to lie behind the heel of the tine to prevent fortuitous disengagement of the platform from the tines, support means projecting downwardly from the base to support the platform with the base inclined at a substantial angle to a supporting surface, said inclination of the base being sufficient and portions of the elements being low enough to permit entrance and withdrawal of the tines from the elements when the platform is resting on a horizontal surface supported by said supporting means.

3. A platform as claimed in claim 2, in which the supports are retractable into the general plane of the base.

4. A platform as claimed in claim 1 having means operated by swinging of the section of the railing outwardly to overlie the periphery of the platform to retract the support means into the general plane of the base.
